NAIL STRIPPER

Edward J. Foote, Benicia, Calif.

Application October 17, 1945, Serial No. 622,762

14 Claims. (Cl. 1—49.7)

1

This invention relates to improvements in nail strippers in which nails are aligned and positioned ready for being grasped by the operator when nailing up boxes from box shook and like structures.

The primary object of the invention is to provide a simple portable device for the purpose, and which may be readily assembled for use and readily adjustable to different sized nails; and one which can as readily be disassembled and compactly boxed ready for transportation.

These objects are accomplished by means of such structure and relative arrangement of parts as will fully appear by a perusal of the following specification and claims.

In the drawings similar characters of reference indicate corresponding parts in the several views:

Figure 1 is a vertical sectional view of the device as set up and assembled ready for use.

Figure 2 is a sectional view of the device as disassembled and boxed ready for transport.

Figure 3 is a plan view of the stripper unit per se.

Figure 4 is a sectional view of the stripper mechanism per se, taken on a line 4—4 of Fig. 3.

Figure 5 is a detached sectional view of the means for fastening the final stripping wires to the positioning plates.

Figure 6 is a top plan view of the feed tray.

Figure 7 is a perspective view of a stripper wire unit.

Referring now more particularly to the characters of reference on the drawings, the numeral 1 designates a relatively shallow box consisting of a body portion 2 and a cover portion 3 hinged together at one edge, as at 4, and adapted when closed together to be fastened by any desired form of latch 5. The box would be provided with any desired form of transport handle or grip 6.

In the body portion 2 is usually disposed a tray 7 adapted to hold a supply of nails, and which tray 7 is provided with a handle 8 whereby it may be readily lifted out and returned to the body.

The side edges of the body 2 are provided with upwardly projecting flanges 9. The cover 3 has corresponding recesses 10 so that when the cover is closed onto the body, the flanges 9 will be received into said recesses and thereby completely enclose the interior of the box. An arm 11 is pivoted on one of the flanges 9, and at its outer end is provided with a notch 12 adapted to fit over one or the other of pins 13 and 14 in order to hold the cover 3 open in different

2

angular positions for the purpose as will presently appear.

Extending across the body 2 between the flanges 9, and fixed to the latter, is a threaded rod 15. Fixed adjacent the ends of this rod are a pair of arms 16 which, at their outer end, rigidly support the nail positioning box 17 so that the box 17 and arms 16, upon turning of the shaft 15, may either be positioned within the box, as shown in Fig. 2, or inclined upwardly and out of the box into the position shown in Fig. 1. When in the latter position the box 17 is detachably connected with the feed tray 18. This feed tray 18 is hingedly mounted to the inside 15 of the cover 3, as at 19, so that it may be either folded into the cover, as shown in Fig. 2, or extended for connection to the box 17, as shown in Fig. 1. When both the box 17 and tray 18 are extended, as shown, they are fastened together by the engagement of spring fingers 20 on the tray 18 being brought into engagement with orifices 21 in the sidewalls of the box 17, and at a point adjacent the then upper edge of the latter, whereby nails placed in the tray 18 will 25 feed by gravity downwardly into the box 17. The relative inclination of the tray 18 with respect to the box 17 may be adjusted by screw clamps 22 slidably in slots 23 in the cover 3, and to which clamps the hinges 19 are secured.

30 The front of the box 17 is open and the side and end walls of the box 17 are made of relatively thin flexible sheet metal. The bottom of the box 17 is formed of a plurality of elongated, inverted V-shaped plates 24 which, at their lower edges, are slightly spaced apart to form slots 25.

35 The back ends of the plates 24 are secured to the end wall of the box, and the two outer plates are secured to the side walls of the box; the 40 slots 25 opening through the open front end of such box. Reinforcing wires 26 extend along the free edges of the plates 24 adjacent the slots 25, and at the open ends of the latter curve away from each other, as at 27, to form a flaring discharge outlet from each slot.

Secured to the bottom of each plate 24 is a relatively rigid arm 28. Each arm 28 is provided at its upper end with a U-shaped yoke 29. Within each yoke 29 is a knurled thumb nut 30; the 50 several thumb nuts being mounted upon a threaded rod 31. By movement of the thumb nuts 30 along the threaded rod 31 the arms 28 may be relatively moved so as to adjust the size of the slots 25. This adjustment is very slight, and 55 is permitted of by reason of the resiliency of the

metal constituting the side walls and end of the box 17.

Each of the arms 23 is fastened to its respective plate 24 by means of laterally diverging flanges 32 which are fastened to the bottom of the corresponding plate 24 by means of small nuts and bolts 33. A hook plate 34 is fastened to the flanges 32, and therefore also to the bottom of each plate 24, by means of the nuts and bolts 33.

Stripper wire units 35 are supported on the hook plates 34. Each such unit comprises a pair of substantially parallel wires 36 having converging outer ends 37 connected by a latch wire 38 which engages one of the hook plates 34, and is clamped to position therein beneath the outer end of the corresponding plate 24 by the tightening of the nut and bolt unit 33.

When all the stripper wire units are in position the converging ends 37 of one unit diverge relative to the converging ends of adjacent units to form an open throat 39, in communication with which are the open ends of the slots 25. Outwardly from the throats 39 the wires 36 of adjacent stripper wire units lie in parallelism substantially as shown in Fig. 3 to form intermediate slots 40. One wire 36 of each stripper wire unit 35 is fixed at its outer end in the rod 15, as at 41, while the opposite wire is provided at its outer end with a hook 42 which detachably engages a shouldered groove 43 on a thumb nut 44 threaded on the threaded rod 15. The wires of the stripping units 35 are relatively flexible, and it will therefore be obvious that the wire 36 of one unit which is mounted on the thumb nut 44 may be relatively adjusted with respect to the wire on the adjacent unit which is fixed to the rod 15 whereby to adjust the size of the slot 40.

Operation

In use, the apparatus is normally enclosed within the box as shown in Fig. 2. When the operator arrives at the point where he wishes to make use of the apparatus he unlatches the cover 3 from the bottom 2 and opens the cover 3 and secures the same in open position with the arm 11. He then lifts the tray 18 and box 17 and latches them together through the medium of the spring fingers 29. In doing this he adjusts the relative angles thereof according to the size of nails that he is going to use and the speed at which he wishes the nails to feed, by moving the screw clamps 22 along the slots 23, and he may also make further adjustment by engaging the notch 12 in one or the other of the pins 13-14.

When the apparatus is set to the desired angles a supply of nails is poured into the supply tray 7. The operator then takes this tray and empties it into the tray 18. Thereupon the nails slide down where they may be temporarily held by means of a removable block 45 wedged between converging side blocks 46 on the lower end of the tray 18. When the operator is ready to commence nailing he removes the block 45, and the nails then slide out of the tray 18 through its open end and into the positioning box 17. In this box, which is inclined at this time, the nails slide by gravity in the V-shaped troughs formed by the inverted V-plates 24, and in doing this a portion of them fall into the slots 25 with their points headed down and their heads up. Those nails which do not thus position themselves flow over the open end of the box 17 and fall back between the wires 36 into the supply tray 7.

Those nails which are positioned in the slots 25 then slide by gravity and out the flared ends of the wires 36 into the throats 39 and hence into the stripping slots 40, coming to rest against the rod 15. The operator then grasps such proportion of these nails as he wishes out of one of the slots 40 and withdraws them through the corresponding throat 39 for nailing in the usual manner.

For nails of different gauges the slots 25 and 40 may be adjusted through the adjustment of the thumb screws 38 and 44. The action of the thumb screws 38 will adjust the lower ends of the slots 25 and the upper ends of the slots 40 simultaneously, and then the lower ends of the slots 40 may be adjusted to conform thereto through the movement of the thumb screws 44.

If for any reason the operator desires to make a change as to the stripper units 35 all he need do is to loosen the nut and bolt units 33 and unhook the latch hooks 42 therefrom and then release the hooks 42 from the flanged grooves 43.

When the operator is finished with any one nailing job he may disconnect the several parts by reversing the connecting operation and then fold them all back into the box ready for transport.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful and upon which Letters Patent are desired:

1. A nail stripper comprising a box which includes a main body and a cover, the cover being hinged to the body at one end, a nail feed tray hinged to the cover and normally enclosed thereby, a nail stripping unit normally hinged to the body and enclosed thereby, and means for connecting the tray and stripper unit together in angular relation when the cover is opened relative to the body; the tray having an open end for discharging nails therefrom into the stripper unit.

2. A device as in claim 1 and including means for adjusting the relative angularity between the tray and unit.

3. A device as in claim 1 in which the cover is provided with a slot, the tray hinge being longitudinally adjustable along the length of the slot.

4. A device as in claim 1 and including, in further combination therewith, a nail supply tray normally disposed in and enclosed by the body, and into which nails may discharge from the stripper unit when the latter is in its angular position.

5. A nail stripper comprising a box including a body and a cover hinged thereto at one end, means for holding the cover open at substantially right angles to the body, a nail feed tray hinged to and normally enclosed by the cover, a nail stripping unit hinged to and normally enclosed by the body, spring fingers on the free end of the tray, orifices adjacent the free end of the unit, the fingers being engageable with the orifices so that the tray and unit may be joined together in relative angular relation when the cover is supported at substantial right angles to the body.

6. A device as in claim 1 in which the pivotal means between the unit and the body comprises a threaded rod, and arms rigidly fixed to the rod; the outer ends of the rods being rigidly connected to the stripper unit.

7. A nail stripper comprising a support, a threaded rod turnably mounted in the support, arms rigidly fixed to the rod, a nail positioning box fixed to the arms, the positioning box being open at its front end and the side and end walls thereof being formed of relatively thin flexible metal, the bottom of the box comprising inverted V-shaped plates fixed to the back end of the box and being spaced apart along their lower edges to form slots, which slots open through the front end of the box, means for adjusting the plates relative to each other to vary the size of the slots, and stripping elements in alignment with each slot, such stripping elements being supported between the bottom of the box and said rod.

8. A device as in claim 7 in which the stripping elements comprise wires spaced apart to form slots which are in register with the slots in the box.

9. A device as in claim 7 in which the stripping elements comprise wires spaced apart to form slots which are in register with the slots in the box, and means for adjusting the position of the wires to vary the size of the slots between the same.

10. A device as in claim 7 in which the stripping elements comprise wires spaced apart to form slots which are in register with the slots in the box, and means for adjusting the position of the wires to vary the size of the slots between the same, such means including thumb nuts threaded upon the rod, one wire of each stripping element being mounted on a thumb nut and the adjacent wire being fixed to the rod.

11. A device as in claim 7 in which the adjusting means comprises a threaded rod supported above the open end of the box, thumb nuts threaded on said last named rod, and arms mounted on the thumb nuts, each arm being connected to the forward end of one of the plates.

12. A nail stripper comprising a support, a threaded rod turnably mounted in the support, a nail stripper unit fixed to the rod turnable therewith to an inclined position, means to hold the unit in such inclined position, such unit including a pair of arms fixed to the rod, a nail positioning box fixed to the outer ends of the arms, the front end of the box being open and

spaced from the rod, the sides and back of the box being made of relatively thin flexible metal, the bottom of the box consisting of a number of inverted V-shaped plates spaced apart along their adjacent lower edges to form slots, a threaded rod supported from the box adjacent the front end thereof, thumb nuts mounted on the last named rod, arms connected with the thumb nuts, each arm being fixed to the forward end of one of said plates, thumb nuts mounted on the first named rod, a wire fixed to each plate adjacent one end thereof and extending to and connected with one of the thumb nuts on the first named rod, and another wire fixed to the plate adjacent the plate on which the first named wire is secured and extending therefrom and being fixed to the first named rod in closely spaced relation to the first wire whereby each pair of wires forms a slot therebetween in register with the slot between the plates to which the wires are secured.

13. A structure as in claim 12 in which the upper ends of the adjacent wires flare apart to form a throat through which nails may be withdrawn from the slot between the corresponding wires.

14. In a nail stripper of the type comprising a base, an upright supported thereon, an upper declining slide to receive in bulk nails to be stripped, a declining lower slide beneath the depressed end of the upper slide to receive nails falling from the depressed end of the upper slide, the improvement of means freely tiltably suspending the lower slide from the upper slide in conjunction with a framework on the lower slide extending beyond the depressed end of the lower slide toward and to a point in spaced relation to said upright, said framework including nail slides, and an adjustable brace rod pivoted at its lower end to the lower end of the framework and selectively securable at its upper end to any one of a plurality of vertically spaced portions on the upright so as to determine and fix the angle of declination of said lower slide and nail slides.
